LOUIS R. MERTENS, OF PHILADELPHIA, PENNSYLVANIA, ASSIGNOR TO CHARLES J. MILLER, OF PHILADELPHIA, PENNSYLVANIA.

STEAM-VALVE.

1,383,005.

Specification of Letters Patent. Patented June 28, 1921.

Application filed April 24, 1920. Serial No. 376,334.

To all whom it may concern:

Be it known that I, LOUIS R. MERTENS, a citizen of the United States, residing at Philadelphia, county of Philadelphia, and 5 State of Pennsylvania, have invented a new and useful Improvement in Steam-Valves, of which the following is a full, clear, and exact description, reference being had to the accompanying drawings, which form a part 10 of this specification.

In the ordinary steam valve, and particularly in that type thereof known as the globe valve, the valve is opened by lifting the valve stem off its seat, and the steam escapes 15 through the annular space between the valve seat and the rim of the valve adapted to seat thereon. In this relative position of the valve and its seat, the valve and its seat are separated by such a relatively slight 20 distance that the friction of the steam upon the adjacent parts cuts, and rapidly wears away, the opposing separated surfaces, and the valve soon leaks. The life of the valve is hence very short and in ordinary installations it is necessary to put up with leaky 25 valves or to assume the serious expense involved in frequent replacements. In installations where it is necessary to throttle the steam flow, the space between the surfaces 30 through which the steam flows is very slight indeed, and the destructive action of the steam is very pronounced.

One of the main objects of my invention is to so construct the valve that its life will 35 be greatly prolonged. Another object of my invention is to so construct the valve that if and when it becomes so worn as to be leaky, the worn members may be replaced with a minimum of expense and trouble. 40 Another object of the invention is to absolutely prevent a back flow of pressure fluid or other gas or liquid in case conditions arise which produce a reversal of pressure in the system. 45 A preferred embodiment of my invention is shown in the accompanying drawings, in which—

Figure 1 is a vertical sectional view of a valve structure embodying my invention, 50 the valve proper being closed.

Fig. 2 is a partial vertical sectional view of the valve structure, the valve being slightly open.

Fig. 3 is a detail elevation of the valve 55 proper and its guide.

Fig. 4 is a view, similar to Fig. 3, of a slight modification.

The valve casing *a* is provided, as usual, with a steam inlet port *b*, a steam outlet port *c*, and a screw-threaded opening in its 60 top adapted to receive the valve stem casing *d*, which is internally threaded to receive the stem *e* having at its top the turnable handle *f*. The stem *e* corresponds to the stem of the valve in an ordinary globe 65 valve structure. Instead, however, of being secured to the valve it is provided, at its lower end, with a head *g* adapted to bear against the valve and hold it to its seat, as hereinafter explained. 70

The valve casing *a* is provided with a central horizontal web or partition *h* separating the valve casing into a steam inlet chamber and a steam outlet chamber communicating with the respective ports *b* and *c*. 75 The web *h* has a central orifice through which extends the cylindrical valve guide *i* having at its lower end an annular flange *j*. The flange *j* is held against the lower wall of the web by means of a neck *k* secured to 80 a cap or closure *m*, threaded into an opening in the bottom of casing *a*. The neck *k* is provided with openings *n* to allow steam to pass from the lower steam inlet chamber of the valve casing *a* into the interior of 85 the valve guide *i*.

A cylindrical valve *o* extends into and is 90 slidable within the valve guide *i* and is closed at its top, the top being flanged to form a head *p* adapted to seat against a valve seat formed on the upper end of the valve guide *i*. In Figs. 1, 2 and 3, the valve seat is formed by beveling the inner edge of the top of the valve guide at *r*, the overhanging part of the valve head *p* being correspondingly beveled at *s*. In Fig. 4 the valve seat is formed by beveling the outer edge of the top of the valve guide at *u*, the overhanging part of the valve head *p* being correspondingly beveled at *v*. 95 100

The valve *o* has preferably a steam tight sliding fit in its guide *i*, but this is not essential, as hereinafter explained. It is provided in its cylindrical wall with openings *t*, for the passage of steam. 105

The valve is maintained closed by screwing down the stem *e* until its head engages the head *p* of the valve *o* and presses it firmly on its seat. In such position, the steam is free to flow through the port *b* 110

into the lower chamber of the valve casing and thence, through the openings *n* of the neck *k*, into the hollow interior of the valve *o*. The steam cannot escape into the upper 5 chamber of the valve casing, because the openings *t* are opposite the solid wall of the valve guide *i*. If, owing to any looseness of fit between the valve and its guide, steam should escape into the annular space 10 thus formed between them, it cannot escape over the valve seat, owing to the valve head being held thereagainst.

By screwing up the valve stem *e* causing it to recede from the guide *i*, the steam pressure 15 acting against the head of the valve will cause it to follow up the stem *e*. The first action will merely cause the valve to be unseated without allowing passage of steam; but after the valve has lifted to the extent 20 required to lift the upper ends of the openings *t* above the top of the valve guide, steam is free to flow into the upper chamber of the valve casing and out the port *c*. The volume 25 of steam flow will vary with the extent to which the valve *i* is allowed to lift above this level, the maximum steam flow being permitted when the openings *t* are entirely uncovered.

It will be observed that there is no flow of 30 steam until the closed end of the valve has receded a substantial distance from its seat so that the friction of steam on the valve seat and on the part of the valve seated thereon is negligible. Hence the wear between 35 the valve and its seat is reduced to a minimum and the life of the valve indefinitely prolonged.

In case of any looseness of fit between the valve and its guide, allowing a film of 40 steam to enter between them, a slight outflow of steam will occur before the openings *t* begin to uncover, but even with a slight lifting of the valve, the space between its head and its seat will be substantially greater 45 than the width of the annular space between the valve and its guide, so that any steam creeping over the seat of the valve will not have sufficient velocity to appreciably cut the valve seat.

50 While the life of my improved valve will thus be substantially prolonged, it has the additional advantage that, in case replacement is necessary, there is no occasion to substitute an entirely new valve structure, as in the ordinary valve, and the replacement is much more simple and inexpensive than in the case of other known valve structures provided with removable valve seats. All that is required is to remove the bottom 55 closure *m*, and the valve guide *i* and valve *o* drop out. A new valve guide and valve are then inserted and the closure restored, and the valve structure is, to all intents and purposes, fully as good as if it were entirely new, there being no factors tending to wear

away the valve casing, its upper and lower closures, or the valve stem.

Another disadvantage of the ordinary valve is that the valve is often placed on a line wherein a reversal of pressures is apt 70 to develop; that is, the pressure in the steam outflow line may rise, or the pressure on the steam inflow line may fall, so as to induce a back flow of steam or other fluid, or liquid, with harmful or even disastrous results. With my invention, any reversal of pressures will result in an immediate closure of the valve regardless of the position of the hand-operated separate valve stem.

It is often necessary or desirable to so position a valve as to allow a very limited flow of steam. This position of the valve is the one wherein the most severe cutting and rapid wearing of the valve and valve seat occur, because, in order to slightly open the 85 valve, the valve is lifted off its seat but very slightly, leaving a very narrow annular space for the passage of the actuating fluid. With my invention, however, it is necessary to separate the valve and its seat a substantial 90 distance before the openings *t* in the valve *o* begin to uncover; so that even when the valve is throttled to its maximum extent, the valve head is lifted to a level where it cannot be injuriously affected by the flowing steam.

While my invention is more particularly intended for use in connection with valves for controlling steam, it is obvious that it may be applied to valves for controlling the 100 flow of any fluid, as, for example, the outflow of water of condensation from a steam trap.

Having now fully described my invention, what I claim and desire to protect by Letters Patent is:

1. A steam valve comprising a valve casing having a bottom opening, a dividing orificed web, a hollow valve guide extending through the orifice in the web and having a flanged lower end, a closure for the bottom opening adapted to engage the lower end of the valve guide and hold it against said web, a perforated hollow valve of smaller diameter than the orifice in the web extending into, and adapted to seat upon, said guide, and a separate stem adapted to be moved in one direction to seat the valve and in the opposite direction to allow steam pressure to unseat the valve.

2. A steam valve comprising a valve casing having a bottom opening, an orificed web in the casing, the casing having an inlet port and an outlet port on opposite sides of said web, a hollow valve guide extending through the orifice in the web, a closure for the bottom opening, an orificed neck on the closure adapted to engage said guide and hold it in fixed relation with the web, a hollow perforated valve extending into said 125

- guide and adapted to seat thereon, said valve being arranged to be inserted through the bottom opening and the orifice in the web, and a separate stem adapted to be moved in 5 one direction to seat the valve and the opposite direction to allow steam pressure, admitted through said neck into the interior of the valve, to unseat it.
3. A steam valve comprising a valve casing 10 provided with a bottom opening, a closure for the bottom opening, a hollow valve guide resting solely on said closure and having a maximum diameter less than that of the bottom opening, a valve seated and supported solely on said guide, a separate stem holding the valve on its seat but adapted to be retracted to allow the valve to lift off its seat, the bottom closure being removable to allow the valve and its seat to be removed 15 through the bottom opening.
4. A steam valve comprising a valve casing provided with inflow and outflow ports and having top and bottom screw threaded 20 openings, a top closure and valve stem guide 25 threaded into the top opening of the casing, a turnable stem threaded in said guide and extending into the valve casing, an orificed
- web within the casing, a hollow valve guide open at both ends and extending through the orifice in the web and having a flanged lower 30 end, a closure threaded into the bottom opening of the casing, a neck carried by the lower closure and adapted to engage the lower end of the guide and hold its flanged end against the web, said neck being perforated to allow 35 flow of fluid thereinto, a hollow valve within said guide and open at its lower end to communicate with the interior of said neck and closed at its upper end, which is exteriorly flanged and adapted to seat upon the upper 40 end of said guide and to be held on its seat by said stem, said flange being of less diameter than the orifice in the web, the valve being provided with perforations adapted, after the valve has been lifted by fluid pressure a 45 substantial distance off its seat, to uncover to allow flow of fluid from the interior of the valve to the part of the valve casing communicating with the outflow port.
- In testimony of which invention I have 50 hereunto set my hand, at Philadelphia, Pa., on this 21st day of April, 1920.

LOUIS R. MERTENS.
